CLAIM

I claim the ornamental design for a jewelry ornament, as shown and described.

DESCRIPTION

FIG. 1 is a front elevation view of a jewelry ornament showing my new design in a position of use with an exemplary pendant chain;

FIG. 2 is a front perspective view thereof, shown with the exemplary pendant chain removed; and,

FIG. 3 is a rear view thereof.

The evenly spaced broken lines are shown for the purpose of illustrating environmental subject matter of an exemplary pendant chain forming no part of the claimed design.

The dot-dash broken lines are shown for the purpose of illustrating the boundaries of the claim and form no part thereof.
